(57) **CLAIM**

The ornamental design for a watering device, as shown and described.

DESCRIPTION

FIG. 1 is a perspective view of a first embodiment of a watering device of my OUR design;

FIG. 2 is a right side elevational view of the embodiment of FIG. 1 thereof;

FIG. 3 is a left side elevational view of the embodiment of FIG. 1 thereof;

FIG. 4 is a front side elevational view of the embodiment of FIG. 1 thereof;

FIG. 5 is a rear side elevational view of the embodiment of FIG. 1 thereof;

FIG. 6 is a top plan view of the embodiment of FIG. 1 thereof;

FIG. 7 is a bottom plan view of the embodiment of FIG. 1 thereof;

FIG. 8 is a perspective view of a third embodiment of a watering device of my our design;

FIG. 9 is a right side elevational view of the embodiment of FIG. 8 thereof;

FIG. 10 is a left side elevational view of the embodiment of FIG. 8 thereof;

FIG. 11 is a front side elevational view of the embodiment of FIG. 8 thereof;

FIG. 12 is a rear side elevational view of the embodiment of FIG. 8 thereof;

FIG. 13 is a top plan view of the embodiment of FIG. 8 thereof; and,

FIG. 14 is a bottom plan view of the embodiment of FIG. 8 thereof.

In these embodiments, portions shown in broken lines are for illustrative purposes and form no part of the claimed design.
